UNITED STATES PATENT OFFICE

FREDERICK L. FULLER, OF TRENTON, NEW JERSEY, ASSIGNOR, BY MESNE ASSIGNMENTS, TO THE NATIONAL CASH REGISTER COMPANY, OF DAYTON, OHIO, A CORPORATION OF MARYLAND

CASH REGISTER

Original application filed October 9, 1922, Serial No. 593,386. Divided and this application filed June 8, 1927. Serial No. 197,598.

This invention relates to cash registers in general and has more particular relation to interlocking mechanisms therefor whereby it is necessary to depress a key in one class prior to a key in another class in order to release the machine for operation.

This application is a division of the inventor's co-pending application Serial Number 593,386, filed October 9, 1922, which became Patent 1,715,910 on June 4, 1929, to which reference may be had for a more complete description of other inventions and features not directly involved in the present application.

15 This invention relates more particularly to cash registers of that class in which the keys are divided into different groups, such as, amount keys and classification keys, so that a depression of keys in different groups may 20 result not only in an indication of amounts but also of special characters to designate the classification of the sale registered, so that in this way each sale may be completely identified. To insure the proper indication, it is 25 desirable to provide an interlocking mechanism between the different groups of keys so that it is always necessary to depress one of the classification keys with an amount key.

It is the main object of the present invention 30 to provide an improved form of interlocking mechanism for effectively performing this function and which is simple in construction, but positive in its action thus precluding any possibility of the disarrangement 35 of the machine, either accidentally or intentionally.

It is a further object of the present invention to include pendants, or key stops, of the usual type which are appurtenant to the interlocking mechanism whereby it will be impossible to depress more than one key in any 40 one group.

In the improved form of indicating mechanism an indicator carriage carrying indicators is raised and lowered by the amount keys so that arms differentially set by the amount keys may select and retain the related indicators elevated during the lowering 45 of the indicator carriage. The interlocking mechanism is so co-ordinated with

the indicator carriage that the latter is normally locked against any movement by the amount keys but an initial depression of one of the clerk's key to indicate the clerk operating the machine will result in slightly elevating the carriage to disable the interlocking device to permit its further reciprocation by the amount keys. To co-ordinate the interlocking device with the indicating mechanism to insure the proper indication is a further object of the present invention.

With these and incidental objects in view the invention consists in certain novel features of construction and combination of parts, the essential elements of which are set forth in appended claims, and a preferred form of embodiment of which is hereinafter described with reference to the drawings which accompany and form part of the specification.

Of said drawings:—

Fig. 1 is a transverse sectional view of the machine taken on the line 1—1 of Fig. 4.

Fig. 2 is an enlarged view looking towards the indicator carriage and showing the details of the same.

Fig. 3 is a top plan view of the means utilized for guiding the slidably mounted indicators at their lower ends.

Fig. 4 is a top plan view of the illustrative machine with the cabinet and other parts omitted.

Fig. 5 is an elevation of the rear of the machine showing clearly the method of supporting the tablet indicators and the improved form of interlock.

Fig. 6 is a view in side elevation of the mechanism utilized for selecting the clerk's indicating tablets.

In the accompanying drawings the improvements are shown in connection with a machine of the general type fully shown in the pending applications for United States Letters Patent, Ser. No. 263,125 filed Nov. 19, 1918, and Ser. No. 283,720, filed Mar. 20, 1919, by Frederick L. Fuller and in the British Patents Nos. 135,465; 140,363; 157,823; 157,824 and 157,825. The Fuller applications aforementioned have matured into Patent 1,742,701, January 7, 1930, and Patent 1,729,-

338, September 24, 1929 respectively. Only such parts of the machine as are directly involved in the present invention are described herein, however, and reference should be made to the applications and patents mentioned for any information desired as to the construction and operation of the rest of the machine.

Although the improvements have been shown applied to a machine of the type disclosed in the above cited applications and patents, it is to be understood that the improvements are capable of being applied to or embodied in other accounting machines without departing from the spirit of the invention.

In cash registers of the type used for illustration the keys are arranged in a plurality of banks or sections, the number depending upon the registering capacity desired. In the present instance, three denominational groups for registering the amounts of the transactions have been provided, and one group comprising two keys which are designated as the "clerk's" or "coupling lifting keys" and several "transaction keys". The amount or value keys are arranged in banks of nine with the exception of the dollars bank which is provided with seven keys. All of the amount keys are arranged to control the extent of movement imparted to a frame, which is common to a particular bank of keys, this differential movement being transmitted to the item type carriers. By the above-mentioned means the amount, the type of transaction and the identifying clerk's character may readily be printed upon a strip of paper as a complete record of the business transacted during a particular period.

The amount and transaction keys in the illustrative machine are normally locked against operation so that it is necessary to depress a clerk's key and this pre-requisite insures the proper designation and indication of the clerk operating the machine.

The tablet indicators employed in the present invention are slidably mounted in a vertically movable indicator carriage. During the initial movement of the indicator carriage by one of the special keys, the carriage will be slightly elevated disabling the interlocking mechanism to permit release of the amount keys. During the first half of an operation of the machine effected by a complete depression of the amount keys the indicator carriage is given a vertical movement carrying with it all of the tablet indicators mounted therein. An arm which has suitable connections to the differential mechanism is adjusted differentially while all the indicators are being elevated so as to select the indicator corresponding to the key depressed. During the second part of the operation of the machine the indicator carriage is lowered and such indicators as have been selected will

be retained in their upper or exposed position by the differentially adjusted arm, thereby exhibiting indications identifying the keys last depressed.

In the illustrative machine the value keys 10, transaction keys 10a, and clerk's keys 11 (Figs. 1 and 4) are pivoted upon a rod 12, and resting upon the rear ends of said keys is a key coupler 13 pivoted as at 14. When the outer end of the keys are depressed, the coupler is rocked clockwise about its pivot so that its rear end enters notches 15 in the rear ends of the keys. The construction and purpose of such key coupler mechanisms are well known in the art.

Connected to the key coupler 13 is a double rack plate 16 (Fig. 1) carrying racks 17 and 171, the connection being such that as the coupler is rocked by the keys the teeth of the racks 17 and 171 alternately engage a pinion 18 (Fig. 4) fast to a shaft 19, which shaft may be designated as the rotation shaft. The result of this is that a complete reciprocation of the coupler will effect a complete rotation of the shaft 19. The shaft 19 carries cams and other devices for operating various parts of the mechanism. The mechanism for effecting rotation of the shaft has not been shown or described in detail because it is so old and well known in the art.

As shown in Fig. 4 there is provided a ratchet wheel 20 secured to the extreme right end of the rotation shaft 19 and against which bears a pivoted spring-pressed pawl 201. This is also a well known expedient and provided for the purpose of insuring a complete operation of the machine.

As shown in Fig. 1 each key is formed with an upwardly extending arm 21 carrying an anti-friction roller engaging a slot 22 in one of a series of plates 23 rigidly mounted in a frame 24 loosely mounted on a shaft 25. The slots 22 in the plates 23 are graduated so that each of the keys will impart a different degree of movement to the frame 24. Secured to the frame 24 is a segmental rack 26. The segmental rack 26 is always in mesh with a pinion rigid with its corresponding item type wheel 27 and sets up numbers corresponding to the value of the key depressed.

Referring to Fig. 4, it is seen that there is a segmental rack 26 for each amount bank and for the transaction key bank and that these racks are concentrated in the central part of the machine whereas the differentially actuated frames extend transversely of the machine substantially the full width of the key-board. It is, therefore, necessary to provide mechanism for transmitting the differential motion imparted to the frames to the actuating racks. To this end the following mechanism is employed.

The differentially actuated frame 24 for the cents bank of keys is mounted upon the segment shaft 25 and has secured thereto at

its left end a sleeve or tube 29 (Fig. 4). Secured to the opposite end of the sleeve is a flanged collar 30 to which is rigidly attached by any desirable means the cents segmental rack 26. The differentially actuated frame 24 of the dimes bank is also provided with a sleeve designated 31, to which is secured its corresponding flanged collar 32 carrying the dimes segmental rack 26. A similar mechanism has been provided for the dollars and transaction banks of keys and in view of the above further description is not deemed necessary.

In the preferred form of embodiment shown in the drawings, the keyboard comprises two special keys 11, designated as has been stated before, the "clerk's" or the "coupler lifting keys". These keys, which are preferably located at the extreme left of the keyboard, have certain other functions, but one of their purposes is to serve as a means whereby the key-coupler 13 may be partially raised to what may be termed the "coupling position", in which position other keys representing the nature and amount of the transaction may be engaged with the coupler so that a complete operation of all the keys so engaged with the coupler may be effected by further pressure applied to any engaged key. The means whereby the coupler 13 is lifted to the coupling point by either of the keys 11 comprises a coupler lifting cam surface 33 (Fig. 1) formed on the rear end of each of the keys and co-operating with a face on a shoulder 34 on the coupler 13. The surface 35 on each key 11 provides a stop face which engages the front edge of the shoulder of the coupler and stops the motion of the key and key coupler. The coupler is retained in its lifted position by the pawl 201 and ratchet 20 hereinbefore described.

In a machine of this kind it is, of course, desirable to prevent the simultaneous operation of two or more amount, transaction, or clerk's keys of the same bank. It is also desirable to prevent the amount and transaction keys from being operated before the depression of a clerk's key and to this end a new form of interlock has been provided.

Referring to Figs. 1 and 5 it will be seen that the rear end of each key is provided with an upwardly facing wedge shaped portion 36. Referring to Fig. 5, a guide plate 37 is attached by any desirable means to a cross bar 38 secured between the main side frames of the machine. The guide plate 37 is provided with guide slots 39 through which the rear ends of the keys project. Between the wedge shaped portions of the keys are a series of pendants 40 which are loosely pivoted to the plate 37 and bar 38. Between each group of keys are special pendants 41 which are pivotally connected to a bar or slide 42 by any suitable means. A spring 43 (Fig. 5) interposed between the bar and the

guide plate forces the bar and attached pendants to the left as viewed in Fig. 5 until stopped by the special hangers 41 co-operating with the wedge shaped portions of the keys.

When the bar 42 is in its normal position, shown in Fig. 5, a clearance space 44 is left between the end of the bar 42 and the side frame. A vertically movable indicator carriage, which is suitably guided on the back frame 45 (Fig. 1) comprises two side plates 46 and 47 and a rod 48 connecting the lower ends of the side plates and overlying the rear ends of the keys as clearly shown in Figs. 1 and 5. Loosely pivoted to the side plate 47 is a pawl 49 (Figs. 1 and 5) its rear end being bent laterally so as to extend normally in the clearance space 44 between the bar 42 and the side frame. The downward movement of the pawl 49 is limited by a stud 50 secured to the side plate 47 co-operating with an upwardly extending projection formed on the pawl.

Referring to Fig. 5 it will readily be seen that when the parts are as shown the keys in the amount and transaction group are locked against depression due to the inability of the pendants to oscillate in either direction. In order to allow the pendants to oscillate, and thus unlock the said keys for depression the rear end of the pawl must be withdrawn from the clearance space. The means for removing the obstruction to unlock the amount keys is controlled by the depression of either of the clerk's or coupler lifting keys 11.

From Fig. 1 it is clear that whenever one of the clerks' keys is depressed to the coupling position, the rear end of the key will contact with the rod 48 and lift the vertically movable indicator carriage high enough to withdraw the pawl 49 from the clearance space 44. At the same time the pendant 51 between the two clerks' keys will be oscillated in one direction or the other, depending upon the key depressed. Whenever pressure is removed from the depressed clerk's key, after the coupler has been lifted and held in its coupling position by the full stroke pawl 201 engaging the ratchet wheel 20 the rear end of the key will drop back toward its normal position until the nose 52 (Fig. 1) rests upon a lug 521 carried by the nose of the coupler and since the indicator carriage will also be held in its partially elevated position, the pawl 49 will be retained a sufficient distance above the slide 42 to allow the keys of other groups to be depressed. Upon the depression of such other transaction or amount keys the bar 42 will be forced to the right (as viewed in Fig. 5) against the tension of the spring 43 and upon the return movement of the keys after their complete depression the said spring 43 will force the bar 42 to the left and the pawl 49 will again drop into the clearance space.

As indicated in the foregoing, the indicator

carriage comprises two vertical side plates 46 and 47 (Figs. 1 and 4) located at the opposite sides of the machine. The side plates are suitably guided by means of guide slots 5 formed in the sides of the back frame 45 and through the medium of the cross rod 48 overlying the rear ends of the keys the carriage is given a complete reciprocation by the keys during each operation of the machine. Further cross connections comprise a bar 53 (Figs. 1 and 5) secured to the side plates and a top member 54 also secured to the side plates 46 and 47 by suitable fastening means.

Referring to Fig. 5 more particularly it will be seen that the amount and clerk's indicators 55 are of the tablet type. The tablets of the clerks' and dollars group carry suitable indicia upon both faces so as to give a front and back indication. The tablets of the two groups of indicators of the dimes banks are each provided on one side with a "¢" sign. The clerks' group of indicators comprises two indicators in the illustrative embodiment, but this number may be changed without departing from the spirit of the invention. As suggested heretofore, two groups of indicators corresponding to the dimes and cents bank are provided, while only a single group is provided for the dollars bank. From Fig. 4 it will be evident that there are ten indicators in each of the denominational groups, the foremost indicator bearing the indicia "0", the adjacent indicator bearing the integer "1" and the remaining indicators bearing indicia corresponding to their order in the group.

The upper portion of each of the tablet indicators is substantially rectangular in form, both sides being provided at their lower portions with a clearance space 56 (Fig. 5) a supporting lug 57, and a guide slot 58 formed substantially in the lower central portion of each indicator tablet. The supporting lug 57 is furthermore provided with a cam edge 59 and a square shoulder 60, the purpose of which will be explained hereinafter.

Secured to the cross member 53 in any desirable way are guide studs 61 (Figs. 1 and 3) provided with guide slots 64 which co-operate with the guide slots 58 formed in the tablets 55. The slots 58 of the tablets terminate at their lower ends in an aperture 62 which is of sufficient size to receive the guide stud 61 (Fig. 3) the purpose of which is to facilitate assembly of the indicators in the frames. The extent of travel of the indicators is less than the length of the slot so that when an indicator is in its raised position the guide stud 61 will be some distance above the aperture so that a positive engaging relationship between the said guide slots 64 and slots 58 will always be maintained. The upper ends of the tablet indicators are furthermore guided by the top member 54 as clearly illustrated in Fig. 4. The member 54 has a

rectangular aperture the sides of which are formed with saw teeth or serrations 551 which co-operate with the edges of the indicator tablets.

As suggested heretofore, all of the groups of indicators are raised during the first operation of the machine and during this movement an arm which is under control of the differential mechanism is set, so as to select and hold the particular indicator of a group which is to remain in its uppermost or exposed position, while the remaining tablets of the group are returned to their lower or normal position. The mechanism for accomplishing this will now be explained, reference being had to the differential mechanism associated with the dimes groups of keys.

Secured to the dimes differentially actuated frame 24 is a segmental rack 65 (Figs. 1 and 4) meshing with a pinion 66 loosely mounted on the rotation shaft 19. Rigid with each pinion 66 is a cam 67, said cam being formed with a graduated portion and a concentric portion. Secured to a sleeve 68 (Figs. 1 and 5) which is concentric with a shaft 69, which in turn, is journaled between the side frames of the machine, is an arm 70 urged downwardly by a spring 710 (Fig. 1). This arm carries at its forward end a roller 77 contacting with the periphery of the cam 67. The arm 70 may be secured to the sleeve 68 in any desirable manner, but in the preferred form of embodiment this is effected by means of a split hub or clamp 77₁ (Fig. 1). The sleeve 68 has also secured to it by means such as just described two selecting arms 71 (Fig. 5) preferably of a resilient material, one for the front and the other for the back group of dimes indicators. The upper end of each arm 71 carries a lug 72 and a cam edge 73 formed thereon.

A similar arrangement of indicator selecting mechanism has been provided for the cents bank. A sleeve 74 (Fig. 5) is also concentric with the shaft 69 and has attached to it a pair of front and back indicator selecting arms 75 for the cents indicators and a horizontal arm 76 carrying a roller 77 (Fig. 4) co-operating with the cents cam 67.

Since there is but one set of indicators for the dollars bank, its sleeve 78 (Fig. 5) has attached to it only one vertical selecting arm 79 and is likewise provided with a horizontal arm 80 (Fig. 4) carrying a roller 77 contacting with the periphery of its corresponding cam 67.

It is, of course, necessary to provide means for aligning and retaining the arms 70, 76 and 80 in their set positions so as to hold the selected indicators in their exposed positions until the next operation of the machine. Referring to Fig. 1 it will be seen that an aligning wheel 82, semi-circular in form is secured to the rotation shaft 19 (Fig. 1) and is adjacent the related arm 70, and the face

of the wheel is provided with a plurality of grooves or tracks 83 ten in number, one for each position of the related arm 70. Referring to Fig. 4, it is seen that the arm 70 is provided with an ear 84 on which is rotatably mounted in any desired manner a roller 85. The periphery of the roller is beveled so as to co-operate with any desired track 83 of the aligning wheel 82. As best shown in Fig. 4, this mechanism is duplicated for the different banks so that the arms 76 and 80 may be aligned in a manner similar to the above.

As best shown in Fig. 1, the graduated portion of the cam 67 related to the dimes bank begins at the concentric portion and extends outwardly in a spiral line, the construction being such that when the roller 77 of the arm 70 is free to contact with the periphery of the cam surface and the cam is rotated by means of the driving rack 65 and pinion 66, the dimes selecting arms 71 will, through the connections described, assume positions under the indicators corresponding to the key depressed.

The sequence of the operation of the parts just described will now be explained in connection with the dimes bank. The normal position of the parts is illustrated in Fig. 1 wherein it is seen that the selecting arm 71 has retained the "9" indicator in its exposed position.

As before explained, a clerk's key 11 must be initially depressed and such depression will raise the coupler to the coupling point where it will be stopped and held in this position. This initial movement of the coupler will raise the indicator carriage to disable the interlocking devices which normally prevent operation of the amount keys to indicate amounts without indicating the clerk operating the machine. This movement of the coupler will rotate the shaft 19 and the aligning wheels 82 sufficient to free the rollers 85 from the tracks 83 and the arm 70 will be urged by the spring 710 to its lowermost position until the roller contacts with substantially the lowest portion of the spiral cam 67. The connected selecting arms 71 (Fig. 5) will at the same time be drawn forwardly to release the "9" tablets until they are in line with the "0" tablets of the two groups. From this, it is evident that upon depression of a clerk's key to the coupling point all the previously exposed indicators will be released. Amount keys representing the value of the keys may now be coupled to the coupler and the coupler and indicator carriage raised to the full extent by completing the downward stroke of the value keys.

During the lifting of the indicator carriage the selecting arm 71 will be adjusted differentially through the connections described and stand in the line of travel of the desired indicator. In the present construc-

tion the arms 71 of the respective banks may be set before the indicators reach their highest position. At substantially the end of the downward stroke of the keys the cam edges 59 of the lugs 57 (Fig. 5) of the tablets which 70 are to be exposed will contact with the cams 73 of the lugs 72 formed on the upper ends of the arms 71, and in so doing, will cam the arms 71 laterally until the lugs 72 clear the supporting lugs 57, whereupon the lugs will 75 spring under the shoulders 60 as clearly shown in Fig. 5. About the time the key reaches the extreme end of its downward stroke the bevel rollers 85 are engaged by their corresponding tracks 83 to align and 80 hold the arms 71 in the position set by the dimes cam 67, during the rest of the operation of the machine.

Upon the return or upstroke of the keys the indicator carriage will descend, carrying with it all of the indicators with the exception of those indicators which are held elevated by reason of their shoulders 60 co-operating with the lugs 72 of their respective arms. If no keys in a particular bank have been 90 depressed, the selecting arm 71 will remain in the line of travel of the "0" indicator and expose the same.

In order to give the indicator carriage sufficient strength and rigidity and to insure 95 that the sides of the frames will receive the same amount of lifting movement the following mechanism is provided. Referring particularly to Fig. 2, it will be seen that the forward edge of plate 46 is formed with 100 teeth 86. The plate 47 is likewise provided with teeth. Journaled between upwardly extending ears 87 of the frame 45 is a shaft 88 (Figs. 1, 2 and 5). Secured to opposite ends of the shaft are two pinions 89 meshing with the teeth 86 of the plates 46 and 47. From the foregoing it is evident that if the indicator carriage be lifted by a key or keys located at one end of the machine a simultaneous and equal lifting movement of the other 105 end of the indicator carriage will be effected through the connections just described.

Inasmuch as there is no differentially actuated frame and segmental rack associated with the two clerks' keys 11 special means 115 must be provided to expose the associated indicators. Adjacent to one of the keys, such as the "B" key (Fig. 4) is a cam plate 90 loosely mounted upon the shaft 25 (Fig. 6). Cam plate 90 is formed with a cam slot 91 120 co-operating with the anti-friction roller carried by the upwardly extending arm 21 of the clerks key "B". The cam plate 90 is further provided with an upwardly extending arm 92 to which is secured a stud 93. An 125 arm 94 is secured to one end of the shaft 69 and is bifurcated at its forward end and provided with an internal cam edge 95 which co-operates with the stud 93 above-mentioned. The arm 94 is further provided with 130

a downwardly extending arm 96 carrying a stud 97. Secured to the rotation shaft 19 is a semi-circular element 98 provided with a groove 99 which at times co-operates with the stud 97. The shaft 69 has secured to its other end a selecting arm 100 (Fig. 5) like the selecting arms heretofore described.

If the parts are as shown in Fig. 6 and the "B" clerk's key is depressed the arm 90 will 10 be cammed backwardly and the rotation shaft 19 and aligning wheel 98 rotated far enough to liberate the stud 97 from co-operation with the guide slot 99. During the further down-stroke of the clerk's key "B" the 15 arm 94 will be cammed upwardly and at substantially the extreme end of the stroke, the stud 97 will contact with the periphery of the aligning wheel and the arm 94 will now be held in its elevated position during the re- 20 turn or upstroke of the keys. The arm 100 moving with the arm 94 will have been rocked rearwardly thus releasing the exposed "A" tablet 55 to a position in line with tablet indicator bearing the character "B". The 25 "B" tablet will then be held in exposed position in the manner explained in connection with the denominational groups of indicators.

It will, of course, be evident that if the 30 clerk's key "A" be depressed during the next operation of the machine, the stud 97 will drop from its highest position to engage the groove 99 of the aligning wheel 98 whereupon the arm 100 will move forwardly to release the "B" indicator and stand in the line of travel of the "A" indicator to accomplish the functions hereinbefore stated. The characters "A" and "B" appear on both sides of the indicator tablets to give both front and 40 back indications.

The above is a description of the operation of the indicator selecting and holding means associated with the amount and clerk's keys. Other devices have been provided for indicating the nature of the transaction but since 45 they form no part of the present invention or are not directly involved, this mechanism will not be explained herein. For details of construction and operation reference may be 50 had to the parent application Serial Number 593,386 filed October 9, 1922.

While the form of mechanism herein shown and described is admirably adapted to fulfill the objects primarily stated, it is to be understood that it is not intended to confine 55 the invention to the one form of embodiment herein shown and described as it is susceptible of embodiment in various forms all coming within the scope of the claims which follow.

What is claimed is:

1. In a cash register, the combination of a series of keys, a second series of keys, pendants including a series of special pendants co-operating with the second series of keys,

a bar connecting the special pendants, an obstruction normally in the path of the bar to prevent oscillation of the pendants to release the second series of keys, said obstruction being capable of being withdrawn to release the second series of keys for operation when a key of the first series is operated. 70

2. In a cash register, the combination of a side frame, a series of clerks' keys, a series of amount keys, pendants including a series of special pendants co-operating with the amount keys, a bar connecting the special pendants, an obstruction placed between the side frame and the bar to prevent oscillation of the pendants to release the amount keys, 75 said obstruction being capable of being withdrawn to release the amount keys when one of the clerks' keys is given a preliminary movement. 80

3. In a cash register, the combination of a series of clerks' keys, a key coupler adapted to be actuated by said clerks' keys to operative position, a series of amount keys, pendants co-operating with the amount keys, an element connected with the pendants adapted to normally prevent the depression of the amount keys, means for retaining said element in its normal position, said means being disabled by the depression of a clerk's key whereby the amount keys are released 95 for depression. 100

4. In a machine of the class described, a key coupler, the combination of a plurality of keys divided into separate groups one group for controlling amounts and the other 105 group for designating classification of sales and for actuating said coupler to operative position, key stops co-operating with the keys of one group, a removable stop device for normally preventing oscillation of the key stops whereby the keys of that group are normally locked, and means under control of the remaining group of keys for disabling the stop device. 110

5. In a machine of the class described, the combination of a plurality of operating keys divided into separate groups, one group for controlling amounts and the other group for designating classification of sales, a movable member, a side frame and a stop device normally disposed between the movable member and the side frame for locking the keys of one group, and means under control of the remaining group of keys for removing the stop device. 115

6. In a machine of the class described, the combination of a plurality of keys divided into separate groups, one group for controlling amounts and the other group for designating classification of sales, means comprising a movable member and a plurality of pivoted key stops for locking the keys of one group, said stops being held in effective position by said movable member, a fixed member, a stop device normally disposed between 120 125 130

the movable member and fixed member and means under control of the remaining group of keys for removing the stop device.

7. In a machine of the class described, the combination of an operating mechanism, amount keys, clerks' keys, means whereby the clerk's keys may impart an initial movement and the amount keys a final movement to the operating mechanism, and means requiring a predetermined sequence of operation between the amount and clerks' keys to control the movements of the operating mechanism comprising a movable member, a fixed member and a stop device normally disposed between said members.

8. In a machine of the class described, a plurality of keys arranged in separate groups, an indicator carriage, a plurality of indicators mounted in said carriage and adapted to be controlled by said keys, means whereby depression of any key will elevate said carriage, means normally preventing depression of keys in one of said groups, and means controlled by said carriage for disabling said preventing means.

9. In a machine of the class described, a plurality of keys arranged in separate groups the keys of one group being normally free to be operated, means normally preventing operation of the keys of the remaining groups, a plurality of indicators each adapted to be controlled by the group of normally locked keys, means whereby the group of normally locked keys select corresponding indicators, means for holding said selected indicators in selected position, and means under control of said first group of keys for releasing previously selected indicators and for simultaneously permitting depression of a key in the group of normally locked keys.

10. In a machine of the class described, a plurality of keys divided into separate groups, a plurality of indicators arranged in groups and adapted to be controlled by the keys of both groups, a plurality of pendants arranged in groups corresponding to said keys and said indicators, and adapted to be shifted upon depression of said keys, a bar connected to one of said pendants in each of a plurality of said groups, an obstruction normally preventing movement of said bar, pendants and keys of the corresponding groups, and means whereby depression of a key in another of said groups not associated with said bar will remove said obstruction to permit the unlocked keys to control the indicators.

11. In a machine of the class described, the combination of a plurality of amount keys, clerk's keys, an indicator carriage, amount and clerk's indicators carried thereby, means under control of the keys for selecting and exposing their corresponding indicators, an interlocking mechanism between the amount and clerk's keys disabled by movement of said

carriage for requiring a predetermined sequence of operation between said amount and clerk's keys and means whereby the clerk's keys shift said carriage.

12. In a machine of the class described, the combination of a plurality of clerk's and amount keys arranged in groups, means including an indicator carriage for exhibiting indicators designating the particular clerk's and amount keys operated, and means comprising a train of elements requiring a predetermined sequence of operation between the clerks' and amount keys, one of said elements being carried by said indicator carriage.

13. In a device of the class described a plurality of keys divided into groups, liftable indicators operated by the keys in each group, separate means for holding an indicator of each group in exposed position, locking means for normally retaining the keys of one group in inoperative position and means operated by the keys of another group for releasing said locking means and for releasing the indicator holding means of each group.
